UNITED STATES PATENT OFFICE

RINZO HAGIWARA, OF TOKYO, JAPAN, ASSIGNOR TO GENERAL ELECTRIC COMPANY,
A CORPORATION OF NEW YORK

FEEDING DEVICE FOR GLASS ARTICLES

Application filed March 11, 1931, Serial No. 521,816, and in Japan March 20, 1930.

My invention relates to apparatus for feeding articles such as bulbs for electric incandescent lamps to machines such as incandescent lamp sealing-in machines. The object is to provide an apparatus whereby there will be a uniform feed of said articles presenting all of them in the same position to the machine with a minimum of breakage. According to my invention, I provide a receptacle comprising a movable bottom, a rotatable inclined skirt surrounding said receptacle and a stationary partition mounted above said skirt. The bottom of the receptacle is gradually elevated to spill the articles on to the skirt and as the skirt rotates, the stationary partition directs them down to the bottom edge of the skirt in single file and they drop therefrom one by one on a suitable guideway. Further features and advantages of my invention will appear from the description which follows of a species thereof and from the accompanying drawings.

In the drawings, Fig. 1 is a perspective view of the bulb feeding machine of my invention; Fig. 2 is a side elevation partially in section of the operating mechanism thereof; Figs. 3, 4 and 5 are vertical sections through my machine in various stages of operation; and Fig. 6 is a plan view of my machine while in operation.

The lamp bulbs 10 which are to be fed by my machine are placed in the receptacle 11 which has a cone-shaped bottom 12, as shown in Figs. 1 and 3. The machine is then started and the bottom of the receptacle is caused to rise until a number of bulbs have tumbled over the top edge of the said receptacle upon the skirt 13 whereupon the bottom is lowered somewhat. The rising action produces the arrangement and disposition of parts illustrated in Fig. 4, and the lowering alters this to that shown in Fig. 5. The motion of the bottom 12 of the receptacle is produced by the mechanism shown in Fig. 2 which is operated by cams 14 and 15 on shaft 16. This shaft is preferably a portion of the machine to which my machine feeds the bulbs and has intermittent movement. The receptacle bottom 12 is raised by lever 17 which engages

the notched portion 18 of rod 19 through pawl 20 and which is engaged by cam 14 through roller 21. The pawl 20 is kept against the rod by spring 22 and carries the full weight of the bottom during its upward and downward movements. On the completion of the downward movement the clutch housed in box 23 engages the rod 19 thereby allowing pawl 20 to move down a notch on rod 19. When roller 24 is against the low part of cam 15, clutch box 23 which is connected to lever 25 through pin 26 is in the position illustrated. In this position, balls 27 of the clutch do not engage rod 19 as the inclinations of the upper surfaces of blocks 28 and 29 cause them to roll away from said rod. When the clutch box 23 and associated parts are in this position. The rod 19 and parts attached thereto are supported by pawl 20. When the roller 24 is in engagement with the high portion of cam 15, the clutch box 23 is in a raised position and the blocks 30 and 31 which have inclined inner surfaces force the balls 27 into engagement with rod 19.

The lamp bulbs 10 which have fallen on to the skirt 13 slide, on account of its conical shape, against the stationary partition 32 which is spiral and provides a spiral path on the upper surface of said skirt, as shown in Fig. 6. The rotation of the skirt by belt 33 causes the bulbs to be directed by the partition 32 down a spiral path to the edge of the skirt where they are swept off on to rods 34 and 35 by plate 36. The bulbs are automatically arranged by this movement into a single file. The outer ends of rods 34 and 35 are supported by yoke 37 on rod 38 which is attached to table 39 by bracket 40 and the inner ends of said rods are supported by bracket 41 which is attached to table 39. The end of the partition 32 is supported by bracket 42 and the various loops thereof are fastened together by straps 43 and 44. Belt 33 which turns skirt 13 is operated through pulley 45 on shaft 46 which is operated from some external source through bevel gear 47 and which is supported by brackets 48 and 49 from the table.

What I claim as new and desire to secure

by Letters Patent of the United States is:

1. An apparatus for feeding bulbs and similar articles comprising a receptacle having a movable bottom, an inclined skirt surrounding said receptacle, a stationary partition mounted over said skirt, means for causing a gradual elevation of said bottom and means for rotating said skirt.
- 10 2. An apparatus for feeding bulbs and similar articles comprising a receptacle having a movable bottom, a conical skirt surrounding said receptacle, a stationary partition mounted over said skirt, means for causing a gradual elevation of said bottom and means for rotating said skirt.
- 15 3. An apparatus for feeding bulbs and similar articles comprising a receptacle having a movable bottom, an inclined skirt surrounding said receptacle, a stationary spiral partition mounted over said skirt, means for causing a gradual elevation of said bottom and means for rotating said skirt.
- 20 4. An apparatus for feeding bulbs and similar articles comprising a receptacle having a movable bottom, an inclined skirt surrounding said receptacle, a stationary partition mounted over said skirt, means for causing a reciprocation and gradual elevation of said bottom and means for rotating said skirt.
- 25 5. An apparatus for feeding bulbs and similar articles comprising a receptacle having a movable bottom, a conical skirt surrounding said receptacle, a stationary spiral partition mounted over said skirt, means for causing a gradual elevation of said bottom and means for rotating said skirt.
- 30 6. An apparatus for feeding bulbs and similar articles comprising a receptacle having a movable bottom, a conical skirt surrounding said receptacle, a stationary spiral partition mounted over said skirt, means for causing a gradual elevation of said bottom and means for rotating said skirt.
- 35 7. An apparatus for feeding bulbs and similar articles comprising a receptacle having a movable bottom, a conical skirt surrounding said receptacle, a stationary spiral partition mounted over said skirt, means for causing a gradual elevation of said bottom and means for rotating said skirt.

In witness whereof I have hereunto set
my hand.

40 RINZO HAGIWARA.
